UNITED STATES PATENT OFFICE.

FRANCIS F. McIVER, JR., OF CHAPPAQUA, NEW YORK.

HEATED-AIR-SUPPLY APPARATUS FOR CLOTH-DRIERS.

1,338,513.

Specification of Letters Patent. Patented Apr. 27, 1920.

Application filed September 19, 1918. Serial No. 254,755.

To all whom it may concern:

Be it known that I, FRANCIS F. McIVER, Jr., a citizen of the United States, and a resident of Chappaqua, in the county of 5 Westchester and State of New York, have invented a new and Improved Heated-Air-Supply Apparatus for Cloth-Driers, of which the following is a full, clear, and exact description.

- 10 Among the principal objects which the present invention has in view are: to avoid the necessity of providing a vertical support for cloth of the character handled by the apparatus herein disclosed; to rest the support 15 of cloth in position for feeding said cloth to the drier; to prevent creasing the cloth while waiting to be dried; to economically heat air for supplying the drier and to modify and control the heater; and 20 to avoid transmission of heat from the pipe supplying heated air to the casing thereof forming a support for the cloth preliminary to drying.

Drawings.

25 Figure 1 is a longitudinal section of an apparatus constructed and arranged in accordance with the present invention, showing in conjunction therewith a fragment of the cloth drier which is supplied by said apparatus;

Fig. 2 is a cross section, the section being taken as on the line 2-2 in Fig. 1;

30 Fig. 3 is a perspective view of the apparatus, showing in conjunction therewith a drier and a roller for the cloth.

Fig. 4 is a plan view of a detail.

Description.

40 The apparatus herein disclosed is employed for drawing tubular woven cloth after the same has been sponged or dampened for shrinking the same. This cloth is preferably woven to form a circular tube, the diameter of which is approximately 45 three feet. The piece turned out by the loom is approximately sixty feet in length. This, of course, may vary. In the trade, however, the piece is considered to contain 50 twenty yards. These pieces are delivered by the sponger to be dried.

The drier usually consists in the relatively short drum 9, the diameter of which is that of the tubular cloth. A spreading guide 55 section 10 is furnished for guiding the cloth onto the drum 9. At the upper end of the

drier, there is usually provided a flattened spreading section 11, by which the cloth is guided to the feeding rollers 12 and 13, the former running idle while the latter is 60 driven. The rollers 12 and 13 are mounted in a frame 14, wherein a rolling center piece 15 for the cloth is guided in a vertical slot 16, said center piece 15 having pintle ends extending into the said slots 16. The center 65 piece 15 and the cloth rolled thereon, rests upon and is driven by the roll 13. By this means there is insured the correspondence between the delivery of the cloth from the rolls 12 and 13, with the peripheral 70 speed of the gradually increasing roll of cloth accumulating about the center piece 15.

Heretofore in order to avoid wrinkling the cloth while damp, it has been suspended vertically below the drier. The drier has 75 been supplied with the heated air, the conduit for which has extended vertically through the suspended cloth. The objection which has arisen has been principally that such a construction has required too 80 much building space.

As seen in the drawings, the conduit 17 is disposed in horizontal position and has an upturned elbow 18. At the delivery end of the elbow 18, is a spider 19. At the center 85 of the spider, there is a socket to receive a pintle 20. The pintle 20 is a part of the construction of the guide section 10 of the heating drum 9.

Surrounding the conduit 17, is a jacket 21. 90 The jacket 21 supports the cloth which is drawn thereover and disposed thereon in suitable folds, while the drying drum is removed. The jacket 21 is rigidly held in a housing 22, cast or otherwise structurally 95 incorporated with a supporting base 23. The end of the housing 22 forms a cone-shaped receiving chamber 24, which is in open communication with the delivery end of the blower 25. The air blower 25, as 100 shown best in Fig. 4 of the drawings, is directly connected with a motor 26. The center feed opening of the air blower is increased or diminished by a gate valve, thereby regulating the quantity of air delivered 105 from the blower 25 to the chamber 24. Heat is furnished for the conduit 17 by a gas torch, the supply pipe 29 whereof is controlled by a valve 30. The pipe 29 enters an open-ended gas-burning tube 31. Centrally 110 disposed in the tube 31, is an open-ended tube 32. The tube 32 is arranged to receive

from the chamber 24 or the blower 25, a column of air, which at the delivery end of the tube 32 passes through the gas delivered to the tube 31 by the supply pipe 29. 5 The effect of the rush of air through the tube 32 on the gas in the tube 31, is to spread or flare the column of gas from the center outward. The gas so spread meets a column of air passing through the tube 33, which 10 surrounds the tube 31, to form an annular space. The inner end of the tube 33 rests within the chamber 24, and is fed with air received therein from the blower 25. The air in passing through the tube 33 around 15 the tube 31, forms a hollow-centered column of moving air, which mixes with the gas delivered from the tube 31 and carries the same past the end of the tube 33, and into the conduit 17. The length of the tube 20 33 is augmented at the delivery and the receiving ends by the telescopic extensions 34 and 35. By moving the extension 35 toward the fan blower 25, a proportionately larger amount of the air delivered by said 25 blower is delivered through the tube 33, with corresponding curtailment of the amount of air which is delivered to the conduit 17 and space between the said conduit and the jacket 21. Likewise, if the extension 30 34 is moved outward from the tube 33, the flame of the burning gas is carried farther into the conduit with the concomitant that the resultant heat in the conduit is somewhat lessened. 35 To prevent the heat within the conduit being transmitted to the jacket 21, the conduit is coated with an asbestos packing 36. The packing 36 is held in place by a metal jacket 37. The air from the chamber 24 40 which passes through the annular space 38 between the jackets 21 and 37, conveys off any heat which may penetrate the packing 36, to the jacket 37. Therefore it is found that during the operation of the apparatus, 45 while the temperature of the heated air within the conduit 17 is usually 500° F., the heat of the jacket 21 is less than 100° F.

When provided with an apparatus such as described, the operation is as follows:

50 The cloth in its tubular form is collected on the jacket 21 in folds. When the entire piece of cloth has been placed on the jacket 21, the drum 9 is reinstated in service position by placing the pinion 20 in the socket 55 provided therefor in the spider 19. The end of the cloth is now brought around over the drum 12. The torch formed by the tube 31 is now ignited. The blower 25 is started and air is blown through the tubes 32, 33, con- 60 duct 17, and the jacket 21. The end of the cloth is drawn over the drum 9 and the spreading section 11 thereof, and is threaded between the rolls 12 and 13 and attached to the center piece 15. The motor 26 is started 65 with the result that air mixed with the heat

from the torch is driven through the conduit 17 and cooling air is driven through the space 38. The motive power for driving the belt 39, which is operatively connected with the roll 13, is started, with the result that 70 the cloth is drawn between the rolls 12 and 13, and the center piece 15 and the cloth accumulating thereon is wound into a roll of cloth. The cloth is drawn from the jacket 21 until the piece is exhausted. The valve 75 30 is then closed to suspend the heat in the conduit 17. The drum 9 is removed from the end of the elbow 18 and a succeeding piece of cloth is deposited on the jacket 21.

It will be understood that the conduit 17 80 is supported by the jacket 21, and the jacket 21 is supported within the housing 22. Any necessary braces between the jacket 37 surrounding the conduit 17 and the jacket 31, may be employed.

The cover 40 in service covers a hand hole through which the torch is ignited at the beginning of the operation of the apparatus.

Claims.

1. A cloth drier, comprising an outer cylindrical casing, an inner hot air pipe located in the casing and spaced from the walls of the casing forming an annular air chamber between the pipe and the casing, 95 a covering of non-heat conducting material around the pipe, the outlet end of said pipe curving upwardly, a flared cloth guide at the outlet end of said pipe, a burner tube projecting into the inlet end of said pipe 100 and spaced from the walls thereof, and an air blast device directing air through the burner tube, around the burner tube into the said pipe, and also through the air chamber between the pipe and the casing. 105

2. A cloth drier comprising a conduit for heated air; a support for said conduit, said support embodying a covering jacket surrounding said conduit and disposed in substantially horizontal position; means for maintaining said jacket and said conduit in spaced relation to form an air passage therebetween; means for forcing a column of air through said conduit; means disposed at the receiving end of said conduit for heating said column of air, said means embodying a gas torch, the delivery end whereof extends into said conduit; and means for distributing the heated medium delivered by said torch, said means embodying an open-ended tube surrounding said torch and disposed in position to be supplied by said means for forcing the air through said conduit.

3. A cloth drier comprising a conduit for heated air; a support for said conduit, said support embodying a covering jacket surrounding said conduit and disposed in substantially horizontal position; means for maintaining said jacket and said conduit in 120 125 130

- spaced relation to form an air passage therebetween; means for forcing a column of air through said conduit; means disposed at the receiving end of said conduit for 5 heating said column of air, said means embodying a gas torch, the delivery end whereof extends into said conduit; and means for distributing the heated medium delivered by said torch, said means embodying open-ended tubes, said tubes being disposed concentric with said torch and with each other, one of said tubes extending through said 35 torch to be infolded thereby and the other of said tubes infolding said torch, said tubes providing a supply of air internally and externally disposed with relation to the fuel delivered by said torch; means for augmenting the volume of air delivered through the tube surrounding said torch, said means embodying a movable extension of said tube, said extension being adapted for augmenting or diminishing the column of air 40 supplied to said conduit and said jacket; and means for increasing the combustion of gases supplied by said torch, said means embodying a movable extension tube telescopically arranged on the tube surrounding 45 said torch and extensible lengthwise thereof.
4. A cloth drier comprising a conduit for heated air; a support for said conduit, said 20 support embodying a covering jacket surrounding said conduit and disposed in substantially horizontal position; means for maintaining said jacket and said conduit in spaced relation to form an air passage 25 therebetween; means for forcing a column of air through said conduit; means disposed at the receiving end of said conduit for heating said column of air, said means embodying a gas torch, the delivery end whereof extends into said conduit; means for distributing the heated medium delivered by 30 said torch, said means embodying open-
- ended tubes, said tubes being disposed concentric with said torch and with each other, one of said tubes extending through said 35 torch to be infolded thereby and the other of said tubes infolding said torch, said tubes providing a supply of air internally and externally disposed with relation to the fuel delivered by said torch; means for augmenting the volume of air delivered through the tube surrounding said torch, said means embodying a movable extension of said tube, said extension being adapted for augmenting or diminishing the column of air 40 supplied to said conduit and said jacket; and means for increasing the combustion of gases supplied by said torch, said means embodying a movable extension tube telescopically arranged on the tube surrounding 45 said torch and extensible lengthwise thereof.
5. An apparatus as characterized comprising a combination of a vertically disposed drier; a supply conduit therefor, said 50 conduit being disposed in substantially horizontal arrangement; an air-circulatory mechanism operatively connected with said conduit; a supporting jacket surrounding said conduit for holding cloth ready for 55 delivery to said drier; and means preventing the heat being exchanged between said conduit and said jacket.
